UNITED STATES PATENT OFFICE.

HARRY H. KUHN, OF MARSHALL, ILLINOIS.

TOOL.

Application filed July 22, 1922. Serial No. 576,795.

To all whom it may concern:

Be it known that I, HARRY H. KUHN, a citizen of the United States, residing at Marshall, in the county of Clark and State 5 of Illinois, have invented new and useful Improvements in Tools, of which the following is a specification.

My present invention has reference to an automobile engine tool.

10 In carrying out my invention it is my purpose to produce a tool for removing carbon from the valve ports of automobile engines of a construction whereby the wall of the port as well as the top thereof will be 15 effectively scraped and the carbon removed from the port received in a cup member associated with the device which prevents carbon falling into the intake manifold that might later be drawn up between the valve 20 and its seat to cause the sticking of the valve on its seat.

A still further object is to produce a tool for this purpose that includes a shank which may have adjustably arranged thereon a 25 sleeve to adapt the tool for varying sizes of engine ports, said shank having integrally formed therewith a cup-like member and having its outer end provided with a handle to which is pivoted a lever that is loosely associated with a two-arm member that is 30 slidable through openings in the shank above the cup, each of said arms being slotted to receive therein a substantially rectangular scraper element, the scraper elements being removable so that all four edges 35 thereof may be employed, while a spring exerts a pressure between the upper and longer arm of the U-shaped member and the scraper element associated therewith to cause the scrapers to effectively contact with 40 the wall of the port and with the top of the valve seat after pressure has been exerted upon the lever to arrange the lower scraper in the port, the carbon being removed by 45 the turning of the tool.

The drawings which accompany and form part of this application, illustrate a satisfactory embodiment of the improvement reduced to practice, and wherein:—

50 Figure 1 is a view illustrating the operation of the tool, parts of the engine block being in section.

Figure 2 is a perspective view of the tool.

55 Figure 3 is a side elevation thereof with parts broken away and parts in section.

As disclosed by the drawing I make use

of a metal member which is preferably in the nature of a rod and which includes a shank portion 1 that has one of its ends rounded upon and connected to the shank to 60 provide a handle 2. The shank, at a suitable distance below the handle has formed thereon a cup-shaped member 3 and above the cup-shaped member the shank is provided with a pair of spaced openings 65 through which is passed the arms of a U-shaped member. The upper arm, or the arm nearest the handle 1, indicated by the numeral 5 is longer than the shorter arm which is indicated by the numeral 4. Pivotally secured to one side of the handle 2, as at 6, there is a lever 7. This lever has its lower end slotted, and passing through the slot is the end or connecting element 8 for the arms of the U-shaped member. The arms 4 and 5 of the U-shaped member have their outer ends provided with longitudinal slots, and received in these slots are square scrapers 9 and 10 respectively. The scrapers are held in the slots by cotter pins 80 11 and 12 that pass through openings in the arms 4 and 5. Surrounding the upper and longer arm of the U-shaped member and exerting a tension against the scraper 9 and the shank 2 there is a helical spring 13. The 85 spring 13 normally swings the lever 7 away from the handle 2 and consequently it is necessary that a pressure be exerted upon the lever to compress the spring and draw the U-shaped member through the openings 90 in the shank to permit of the lower scraper 10 being arranged in the valve port 14 of the engine. When so positioned, pressure upon the lever is released which permits of the expansion of the spring that draws on 95 the U-shaped member bringing the lower scraper element 10 into frictional contact with the wall of the port and the upper scraper member 9 in contacting position with the valve seat or the engine block directly above the port. The carbon removed from the port is received in the cup-shaped member so that danger of the same later creating trouble by being drawn on to the valve seat will be thus entirely overcome. 100

The stem may be lengthened to accommodate the tool to different sized engine ports by arranging a sleeve 15 thereon.

By providing the scraper members 10 of square or rectangular shape, all of the edges 110 thereof may be employed in scraping, it being, of course, understood that the scraper

members are removably associated with the arms of the U-shaped member, and it is believed that the foregoing description, when taken in connection with the drawing will fully set forth the construction, operation and advantages of the improvement to those skilled in the art to which this invention relates.

Having described the invention, I claim:—

1. A tool for the purpose set forth including a shank having a handle at one end thereof, a cup-shaped member integrally formed on the shank, a lever pivotally secured to the handle, a U-shaped member 15 slidable through the shank and loosely engaged by the lever, removable scraper members on the arms of the U-shaped member, and spring means influencing the U-shaped member in one direction.
2. In a tool for the purpose set forth, a shank, a sleeve adjustably received on one end thereof, a cup-shaped member above the sleeve, a handle on the opposite end of the shank, a lever pivotally secured to the handle, a U-shaped member 25 slidable through the shank above the cup-shaped member and having its outer arm longer than its inner

arm, a loose connection between the U-shaped member and the lever, scraper blades removably secured in the outer ends of the arms 30 of the U-shaped member, and a spring on the longer arm of the U-shaped member exerting a tension between the shank and the scraper member on said arm.

3. A tool for the purpose set forth, comprising a shank, a sleeve adjustably arranged thereon, a cup-shaped member on the shank above the sleeve, a handle on the shank above the cup-shaped member, a lever pivotally secured to the handle and having an inner slotted end, a U-shaped member having its arms slidable through the shank and its connecting element received through the slot in the lever, the outer arm of the U-shaped member being longer than the inner arm thereof, and both of said arms being slotted from their ends, square scraper elements received in the slots and removably connected to the arms, and a spring on the longer arm exerting a tension between the shank and the scraper member on said arm. 35 40 45 50

In testimony whereof I affix my signature.

HARRY H. KUHN.
